BUBBLE TYPE WINDSHIELD FOR BOATS

Henry Gesswein, Stockton, Calif.

Application November 8, 1954, Serial No. 33,020

Term of patent 14 years

(Cl. D71—1)

Fig. 1 is a perspective view of a bubble type windshield for boats embodying my new design. The broken-line portions are for the purpose of illustration.

Fig. 2 is a front elevation of one of the windshield sections, detached.

Fig. 3 is a sectional plan view taken on line 3—3 of Fig. 2.

Fig. 4 is a transverse section taken on line 4—4 of Fig. 2.

I claim:

The ornamental design for a bubble type windshield for boats, as shown and described.
